UNITED STATES PATENT OFFICE.

ALFRED J. SHIPLEY, OF WATERBURY, CONNECTICUT, ASSIGNOR TO THE SCOVILL MANUFACTURING COMPANY, OF SAME PLACE.

DESIGN FOR A TROUSERS-HOOK.

SPECIFICATION forming part of Design No. 30,232, dated February 21, 1899.

Application filed September 9, 1897. Serial No. 651,143. Term of patent 14 years.

To all whom it may concern:

Be it known that I, ALFRED J. SHIPLEY, a citizen of the United States, residing at Waterbury, in the county of New Haven and State of Connecticut, have invented and produced a certain new, original, and useful Design for Trousers-Hooks, of which the following is a full, clear, and exact description.

This design relates to that form of garment-clasps known in the trade as "trousers hooks and bars." Such trousers hooks and bars are made in pairs, each pair comprising a hook and a bar.

The present invention comprises a design for the hook of a trousers hook and bar.

In the accompanying drawings, forming part of this specification, and in the two figures of which like parts are similarly designated, Figure 1 is a perspective view of the hook, and Fig. 2 is a longitudinal section thereof.

As shown in the drawings, the leading or material feature of my design consists of the rounded hollow protuberance *a*, arranged at one end of the hook *b*, and the design as a whole comprises a hook for a trousers hook and bar having the said protuberance arranged substantially as shown and described.

Having described my invention, what I claim as new, and desire to secure by Letters Patent, is—

The design for a trousers-hook, substantially as herein shown and described.

In testimony whereof I have hereunto set my hand this 31st day of August, A. D. 1897. 35

ALFRED J. SHIPLEY.
